CLAIM

The ornamental design for a storage bucket, as shown and described.

DESCRIPTION

FIG. 1 is a top perspective view of a storage bucket, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded, top perspective view thereof;

FIG. 10 is a front perspective view thereof, shown with the lid opened;

FIG. 11 is an exploded, front perspective view thereof; and, FIG. 12 is an enlarged detail view of area 12 in FIG. 1. The broken lines in the drawings illustrate the portions of the storage bucket, which form no part of the claimed design. The dash-dot-dash broken lines encircling the enlarged views are for annotative purposes only and form no part of the claim thereof.
